The ornamental design for a stool, as shown and described.

DESCRIPTION

FIG. 1 is a front, top, right perspective view of a stool, showing my new design;

FIG. 2 is a rear, bottom, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged, rear, bottom, left perspective view of detail "9" identified in FIG. 2.

The dashed broken lines in the figures illustrate portions of the stool that form no part of the claimed design. The dash-dot-dash broken lines in FIGS. 2 and 9 depict the bounds of the enlarged views and form no part of the claimed design.
